(57) **CLAIM**

The ornamental design for height adjusting chair arm, as shown.

DESCRIPTION

FIG. 1 is a perspective view of a first embodiment of the height adjusting chair arm showing my new design for a right side of a chair which is shown in phantom;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof;

FIG. 7 is a bottom plan view thereof; and,

FIG. 8 is a perspective view of an alternate embodiment mirror image, similar to FIG. 1 except the chair arm is for a left side of the chair.

The phantom line shown in FIG. 1 is for illustrative purposes only and forms no part of the claimed design.
